UNITED STATES PATENT OFFICE.

CHARLES P. SCOTT, OF NEW YORK, N. Y.

DESIGN FOR A CASING FOR PENDENT CEILING CUT-OUTS.

SPECIFICATION forming part of Design No. 33,193, dated September 11, 1900.

Application filed May 29, 1900. Serial No. 18,468. Term of patent 3½ years.

To all whom it may concern:

Be it known that I, CHARLES P. SCOTT, a citizen of the United States, residing in the borougn of Manhattan, city of New York, 5 State of New York, have invented and produced a new and original Design for a Casing for Pendent Ceiling Cut-Outs, of which the following is a specification, reference being had to the accompanying drawings, forming 10 a part thereof.

Figure 1 is a view of the casing from below. Fig. 2 is a side elevation, and Fig. 3 is an end elevation of the same.

As shown in the drawings, a leading or material feature of the design is the boss or rosette 15 3 on the cover 2 of the rectangular cas-

ing 1. Said cover 2 is ornamented with ribs and grooves, substantially as shown. The contour of the said boss 3 is also of an ornamental design, substantially as shown, and 20 said boss is perforated with the cylindrical hole 4.

Now, having described my invention, what I claim as new, and desire to secure by Letters Patent, is—

25 The design for the casing of a pendent ceiling cut-out, substantially as shown and described.

CHARLES P. SCOTT.
